4 Claims. (Cl. 227—10)

This invention relates to bolts for bolt driving or ramming tools having a barrel-type housing containing a piston having a rod or ram portion and actuated by a charge, such as an explosive charge. The piston or ram drives the bolt from the barrel of the tool into an opposed or counter surface, such as a panel or wall. This invention relates also to a tool for driving in such bolts.

The tools of this type which have a bolt driving piston member have the advantage in comparison with similar tools which project the bolt from the barrel that the handling of these piston operated tools is less dangerous and that they may be applied more suitably for driving bolts or nails into a surface or a material which is less resistant. They may be adjusted to operate through a limited stroke length or striking distance of the piston whereby the ramming depth for the bolt is also limited or adjusted.

It is a feature of the invention to provide a bolt which is particularly adapted for this type of bolt driving tools, especially for use with the piston operated tool disclosed herein. Various modifications of the head portion of the associated bolt are disclosed herein. The bolt may be driven into a panel or wall or the like although neither the bolt nor the tool has a special arrangement or elements for guiding the bolt while it is driven out of the barrel into the opposed surface. It is therefore also a feature of the invention to provide a bolt driving tool of the type described above which is especially suited for working with a bolt according to the invention.

It is a further feature of the invention to provide a device by means of which the bolt may be easily inserted and lodged in the tool barrel in engagement with the piston.

It is another feature of the invention to provide a retaining element which is applied to the end of the bolt facing the piston or the head end of the bolt. The retaining element permits a clamping or wedging insertion into a front end recess of the piston. After being thus secured to the piston the bolt extends freely along the axis of the barrel and requires no special guiding means inside the barrel. The bolt is easy to manufacture and the bolt driving tool may also be produced easily and inexpensively because it no longer requires a barrel containing means for guiding the bolt.

The clamping element or retaining body of the bolt may have a number of different forms. For this purpose the outer end of the piston is merely provided with a recess or opening for receiving a retaining element.

Another feature of the invention is the provision of a loading rod for introducing and lodging the bolt with its retaining member in the front recess or opening of the piston and consists of a guide tube or loading tube having a bore for receiving the bolt shaft with a front portion or projection adapted to bear against the end of the bolt which carries the retaining member or against the retaining member itself, the diameter of this projection being smaller than the diameter or opening of the recess in the piston which receives the head end of the bolt.

In the tool disclosed herein, which is particularly designed to drive in the bolts of this invention, the piston is divided into a piston sleeve which receives the adjacent end or the head end of the bolt, a ram or piston rod por-

2

tion projecting forwardly of the piston head and adapted to enter the piston sleeve bore, a part which lies rearwardly of the piston head on the side adjacent the drive chamber, and an elastic buffer member arranged between the piston sleeve and the piston head and surrounding the piston rod portion. The elastic buffer reduces the impact or shock of the piston during the injection of the bolt thus causing less damage to work materials such as strips and boards which are to be connected to a wall by means of the bolts. While driving in the bolt, the piston rod pushes the bolt head from the opening in the piston sleeve.

It may be desirable to provide in the barrel containing the piston a tensioning member which bears resiliently against the piston sleeve or piston head and disposed axially of the barrel in the manner of a tensioning rail or plate. Such a tensioning member allows an adjustment of the impact force or stroke of the piston as this member, which bears radially against the piston sleeve or the piston head, makes it possible to set the piston at different intervals or distances from the driving chamber.

Additional features and advantages of the invention will appear from the following description in combination with the accompanying drawings which illustrate for the purpose of examples various embodiments including the elements which are necessary to a full understanding of the invention.

FIGURE 1 shows a longitudinal section through the front portion of a charge operated tool according to the invention with a bolt set into the piston sleeve.

FIGURE 2 is a longitudinal section through the tool according to FIGURE 1 after discharge of the tool and insertion of the bolt.

FIGURE 3 shows a longitudinal section of the loading tube for setting the bolt in the barrel.

FIGURE 4 shows a bolt with an enlarged threaded head.

FIGURE 5 shows a part of the threaded bolt head of FIGURE 4 in an enlarged view.

FIGURE 6 shows a bolt with a threaded head whose diameter is smaller than the diameter of the piston rod.

FIGURE 7 is a side view, partly in longitudinal section, of the end of the piston rod with an inserted bolt of modified form.

FIGURE 8 is a section similar to FIGURE 7 showing a bolt with a rivet type head.

FIGURE 9 shows a section similar to FIGURE 8 with a bolt having a conical retaining ring around the bolt shaft.

FIGURE 10 shows a section similar to FIGURE 7 in which the bolt head has a conical retaining member axially at the outer end.

FIGURE 11 shows a partial section similar to FIGURE 10 in which the bolt has a retaining flange below the head.

FIGURE 12 is a partial section similar to FIGURE 11 with a retaining member in the form of a wire ring surrounding the bolt shaft.

The bolt driving tool of the invention illustrated generally in FIGURES 1 and 2 comprises a housing 1 in the form of a barrel in which a piston 2 is received for reciprocation and adapted to be driven forward in the barrel by igniting a charge indicated by numeral 17 placed in a firing chamber at the rear end of the barrel in order to drive the bolt 3 into a wall or the like. A piston sleeve 4 is provided in the front end of the barrel to receive the bolt head. The piston 2 has a ram portion 5 which is received centrally in the opening or bore of the piston sleeve. Between this sleeve 4 and the piston 2 a buffer member 6 is arranged, which is made of an elastic material as shown in the embodiment illustrated in the drawing. The buffer has such a form, preferably including an intermediate diametrically reduced portion, that it

may be compressed axially between the piston 2 and piston sleeve 4.

A tensioning member 7 inserted into the side of the barrel bears against the piston sleeve 4 due to a spring 8 which presses it inwardly. The tensioning member 7 provides that the piston 2 may be inserted to a greater or smaller degree into the driving chamber 18 without sliding out of the barrel. Rearwardly of the piston head is the driving portion of the piston which is received in the driving chamber.

In the embodiment of FIGURE 1 the shaft of the bolt is provided at the end below the head 9 with a retaining or clamping element 10 of elastic material by means of which the bolt is set into the bore of the piston sleeve so that the bolt extends freely axially of the barrel away from the piston sleeve.

The bolt shown in FIGURE 4 has a threaded head 11. Into the threads of this threaded head portion a wire spiral 12 is placed and extends with its outer diameter slightly beyond the outer diameter of the threads as shown in FIGURE 5. Before inserting the bolt head into the piston sleeve the wire spiral is preferably not in contact with the sides of the threads.

FIGURE 6 shows a bolt which has a smaller shaft diameter than the bore of the sleeve or of the piston rod and no head. The end of the bolt adjacent the sleeve has a threaded portion. On this end an elastic retaining or clamping member 13 is placed before setting it into the sleeve opening.

For the purpose of setting the bolt into the piston sleeve 30 a guide tube or loading tube 15 is employed whose end 16 facing the piston sleeve is reduced to the diameter of the bore in the piston sleeve. The position of the application or use of the loading tube is indicated in dotted lines in FIGURE 1.

FIGURE 2 shows the charge operated tool in the position after driving the bolt into an opposed surface.

In the embodiments of FIGURES 7-12 the bolt is set directly into the forward end of the piston rod whose end facing the bolt has a recess 19 for this purpose.

In the embodiments of FIGURES 7, 10, 11 and 12 the bolt is provided with a threaded head 11 while in the examples of FIGURES 8 and 9 it has a cylindrical nail-type head 11'.

According to FIGURES 7-9 a metal clamping ring 20 is disposed on the bolt shaft in the vicinity of the bolt head, this ring being made for example of brass. The bolt may be furnished with the clamping ring but it is possible that the clamping ring be furnished separately so that it has to be placed on the bolt shaft before using the bolt. The clamping ring may also be in the form of a split ring.

In FIGURES 7 and 8 the opening of the bore which receives the bolt head may be of a conical form diverging inwardly toward the axis and the conical surface is indicated by numeral 21.

In the embodiment of FIGURE 9 the outer circumference of the clamping ring is conical. The conical outer circumference is indicated by numeral 21'. It should be understood that the opening of the bore receiving the bolt head and the clamping ring may be formed conically so as to complement each other.

FIGURE 10 shows a bolt whose head 11 has a conical axial extension 22 and the bottom of the recess 19 in the end of the piston rod is provided with a corresponding conical recess 23.

The bolt shown in FIGURE 11 is provided with an annular clamping flange 20'. The receiving opening in the front part 19' is formed conically. In this embodiment the peripheral surface of the flange and the receiving opening of the piston may be conical. Similarly the peripheral surface of the flange alone may be conical.

According to FIGURE 12 a clamping ring 20" of wire may be arranged on the bolt shaft, by means of which the bolt is clamped securely in the recess 19 which has a part

21 which diverges conically outwardly. The clamping ring or wire ring 20" may be of any suitable material, such as copper, brass, iron or the like. It is also possible to make the wire ring or the annular retaining member of a plastic material. The end of the wire which forms the ring or annular retaining member need not be connected, and may have a desired cross-section such as round, oval, rectangular, square or the like.

In each of the embodiments the size of the angle of the conical surface is so chosen that it provides an automatic clamping action.

A guiding or loading tube as illustrated in FIGURE 3 may also be employed for inserting the bolt of FIGURES 7-11 into the piston.

What is claimed is:

1. A charge operated bolt driving tool comprising in combination

- a barrel having a bore at one end for receiving and ejecting a headed bolt having a frictionally engaged retaining means associated therewith,
- a firing chamber at the other end of said barrel for receiving a firing charge,
- a driving chamber between said bore and said firing chamber and communicating therewith, and
- a composite piston member received for reciprocation in said barrel and including

- (a) a piston head having a diameter slightly less than the inner diameter of said bore,
- (b) a ram portion extending from said piston toward said one end of said barrel centrally of said bore,
- (c) a driving portion extending centrally from said piston head toward said other end of said barrel and received for reciprocation in said driving chamber,
- (d) a substantially smooth walled axial recess in the end of said ram portion for receiving the head of said bolt and said retaining means.

2. The bolt driving tool according to claim 1 wherein said recess has an outwardly diverging frusto-conical wall whose base diameter is less than the diameter of said retaining means.

3. A charge operated bolt driving tool comprising in combination

- a barrel having a bore at one end for receiving and ejecting a headed bolt,
- a firing chamber at the other end of said barrel for receiving a firing charge,
- a driving chamber between said bore and said firing chamber and communicating therewith, and
- a composite piston member received for reciprocation in said barrel and including

- (a) a piston head having a diameter slightly less than the inner diameter of said bore,
- (b) a ram portion extending from said piston toward said one end of said barrel centrally of said bore and having a relatively small diameter leaving an annular space between itself and the inner surface of said bore,
- (c) an axial recess in the end of said ram portion for receiving the head of said bolt,
- (d) retaining means associated with said bolt head for engaging the walls of said-recess to fix said bolt on said ram portion coaxially therewith,
- (e) a driving portion extending centrally from said piston head toward said other end of said barrel and received for reciprocation in said driving chamber,
- (f) a piston sleeve slideably received on said ram portion at its outer end and reciprocating therewith,
- (g) a buffer means of resilient material disposed between said piston head and said piston sleeve and filling substantially said annular space be-

tween said ram portion and the inner surface of said bore, and

(h) a circumferentially reduced intermediate portion on said buffer means allowing a limited axial compression of the resilient material of said buffer means under the bolt driving impact, said resilient material moving said piston head inwardly sufficiently to separate said ram portion from the bolt head upon returning into its normal distended position.

4. The bolt driving tool according to claim 3 wherein said buffer means engages the outer surface of said ram portion at its inner periphery and engages at its outer

periphery the inner surface of said bore at least at the ends.
